(57) CLAIM

The ornamental design for a pocket with stitching for a clothing article, as shown and described.

DESCRIPTION

FIG. 1 is a rear view of a first embodiment of a pocket with stitching for a clothing article showing the new design; FIG. 2 is a left side view of the design shown in FIG. 1; FIG. 3 is a right side view of the design shown in FIG. 1; FIG. 4 is a rear view of a second embodiment of a pocket with stitching for a clothing article showing the new design; FIG. 5 is a left side view of the design shown in FIG. 4; FIG. 6 is a right side view of the design shown in FIG. 4; FIG. 7 is a rear view of a third embodiment of a pocket with stitching for a clothing article showing the new design; FIG. 8 is a left side view of the design shown in FIG. 7; and, FIG. 9 is a right side view of the design shown in FIG. 7. The figures include broken, solid, and dash-dot-dash lines. The areas within the solid lines and inside the dash-dot-dash lines form the claimed design. The dash-dot-dash lines illustrate an unclaimed boundary of the claimed design. The broken lines shown in the figures are included for the purpose of illustrating parts of the pocket with stitching for a clothing article and form no part of the claimed design.
